UNITED STATES PATENT OFFICE.

SAMSON BORGNISS, OF PHILADELPHIA, PENNSYLVANIA.

LOOM FABRIC PROTECTOR.

Application filed November 16, 1926. Serial No. 148,661.

My invention relates to new and useful improvements in a loom fabric protector, and has for its primary object to provide means operative by the loom shuttle, which will permit proper operation of the loom if the shuttle enters a shuttle box, but which will stand in the way of a sliding member should the shuttle fail to enter the box, thus causing the operation of a suitable clutch or equivalent mechanism to stop the loom.

Another object of the invention is to provide the finger and foot of a lever mounted upon a protecting rod carried by the loom lay, said finger cooperating with the swells of the shuttle box so as to be actuated thereby upon entrance of the shuttle in the box, which action will lift the lever foot and permit it to pass over the reach rod during the oscillations of the lay, and said foot when in its lowered position engaging the end of the reach rod to operate the loom stop mechanism.

With these and other ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings forming a part of this application, in which:

Fig. 1, is a fragmentary plan view of a loom in the region of the shuttle box.

Fig. 2, is a fragmentary end view thereof, with a portion of the running stand broken away and shown in section.

In carrying out my invention as here embodied, 3 represents the breast beam of a loom having a hanger 4 secured thereto in which are threaded the adjustable bolts 5, and said bolts pass through the slot 6 in the running stand 7, which may be of usual or any desirable construction.

On the running stand rests a portion of the reach rod 8 having an upturned toe 9 at its inner end, which toe is curved inward relative to the reach rod at its upper end. The opposite or outer end of the reach rod is connected at 10 with the lever 11 of a loom stop mechanism or clutch, and as shown this lever 11 has one end of a rod 12 connected thereto, which rod leads to the actual clutch or loom stop mechanism. The lever 11 is

mounted on the handle shaft 11^a journalled in supporting means 11^b carried by any suitable part of the loom, as by the breast beam 3.

The reference numeral 14 denotes the lay which is oscillatory as usual and carries the shuttle boxes one of which is illustrated and designated by the numeral 15 and is provided with the usual swells 16.

Cooperating with the swells of the shuttle box is a finger 17 secured upon the protecting rod 18 journalled in brackets 19 on the lay, and at one end of the protecting rod is secured the foot 20 normally assuming the position shown in full lines in Fig. 2, so that the toe 9 of the reach rod is in the path of travel of the foot 20, except when a shuttle is within a shuttle box causing the finger 17 to be moved into the position shown in dotted lines in Fig. 2, so that the protecting rod 18 is rotated to lift the foot 20, as also shown by dotted lines in Fig. 2.

In practice when a shuttle enters its shuttle box in the proper manner, the lever made up of the arm 17 and foot 20 is actuated so that the parts are moved to the positions shown in dotted lines, and therefore as the lay oscillates, the foot will pass over the toe 9 of the reach rod, and the loom will operate properly.

If for any reason the shuttle does not enter the box, the foot 20 will remain in the position shown in full lines, and as the lay moves inward, the end of said foot will engage the toe 9 and actuate the reach rod 8 thereby transmitting motion to the loom stop mechanism or clutch and the loom will be stopped.

Of course I do not wish to be limited to the exact details of construction as herein shown as these may be varied within the limits of the appended claims without departing from the spirit of my invention.

Having thus fully described my invention, what I claim as new and useful is:

1. The combination with a loom including a breast beam, a lay, a shuttle box and a loom stop mechanism, of a hanger carried by the breast beam, a running stand adjustably mounted on the hanger, a reach rod connected with a portion of the stop mechanism and having its free end slidably mounted in the running stand, a toe at the outer end of the reach rod and having an inturned upper end, brackets secured to the lay, a loom protecting rod journalled in said brackets, a finger

mounted on said rod and coacting with the shuttle box, and a foot secured to the protecting rod with the free end of said foot overlying the reach rod, the toe of said reach rod being in the path of travel of the foot during the absence of a shuttle in the shuttle box, said foot being raised through the medium of the finger when a shuttle is in the shuttle box so as to pass over the toe.

2. The structure set forth in claim 1, 10 wherein the shuttle box is provided with swells so that the finger will be indirectly actuated by the shuttle through the medium of said swells coacting with said finger.

In testimony whereof, I have hereunto affixed my signature.

SAMSON BORGNIS.
